UNITED STATES PATENT OFFICE.

JOHN B. VAN HOUTEN, OF NEWARK, NEW JERSEY.

DESIGN FOR AN EAR-RING.

SPECIFICATION forming part of Design No. 14,856, dated March 4, 1884.

Application filed November 21, 1883. Term of patent 7 years.

To all whom it may concern:

Be it known that I, JOHN B. VAN HOUTEN, a citizen of the United States, residing at Newark, in the county of Essex and State of New Jersey, have invented and produced a certain new and original Design for Ear-Rings; and I do hereby declare the following to be a full, clear, and exact description of the design, such as will enable others skilled in the art to which it appertains to make and use the same, reference being had to the accompanying drawings, and to letters of reference marked thereon, which form a part of this specification.

Figure 1 is a front elevation, and Fig. 2 a side view, which views are deemed sufficient to fully illustrate the design.

The leading feature of the design consists in the ear-ring having the configuration substantially as described.

Referring to the drawings, *a* is a ring-shaped portion of the ear-ring, which is enlarged at the lower part, as at *b*. Opposite said enlargement and adjacent to the ear-wire the ear-ring is shield-shaped, as at *c*, at the lower end, the lower end of which shield-shaped portion and at about the center of the ring-shaped por-

tion, as at *d*, the ear-ring projects, as shown in Fig. 2, and radiates or is star-shaped, as shown. The ring-shaped part is enlarged at each side of the center or star-shaped portion, as at *e e*. Again, the enlarged portion, at its lower edge, may have the recess *f* formed in the lower edge thereof. Said enlarged portion partially surrounds the knobbed portion *g* of the ear.

35

What I claim is—

The design for an ear-ring, the same consisting in an ear-ring having the annular or ring-shaped portion *a*, enlarged at *b*, shield-shaped or broadened, as at *c*, and projecting downward, as at *d*, to the center or nearly to the center of the ring-shaped portion, and there expanding, substantially as shown and described.

In testimony that I claim the foregoing I have hereunto set my hand this 16th day of November, 1883.

JOHN B. VAN HOUTEN.
